BY

J. P. Fitch

ATTORNEY.

UNITED STATES PATENT OFFICE.

HEINRICH HENRICH, OF NEW YORK, N. Y.

FINGER-RING.

SPECIFICATION forming part of Letters Patent No. 293,874, dated February 19, 1884.

Application filed November 3, 1883. (No model.)

To all whom it may concern:

Be it known that J. HEINRICH HENRICH, of the city of New York, in the county and State of New York, have invented a new and useful Improvement in Finger-Rings, of which the following is a full, clear, and exact description, reference being had to the accompanying drawings, forming part of this specification.

10 My invention relates to a finger-ring; and it consists in the devices hereinafter shown and described, whereby the band encircling the finger is adjustable as to its length, so that the ring may be varied in size to fit the finger of the wearer.

15 Figure 1 is an enlarged edge view, partly in section, of a finger-ring containing my invention. Fig. 2 is a side view of the same. Figs. 3, 4, 5, and 6 are enlarged views in detail of 20 the devices and their arrangement, by which I secure the adjustability of the length of the band of the ring and fasten the same to the head or crown, as will appear in the description.

25 B is the head or crown piece, which may be constructed to constitute the setting of a stone in the usual way. This head or crown is extended laterally on each side, forming wings or lugs b b', as shown. These lugs are recessed 30 inwardly from their outer ends, as shown in Fig. 1, and these recesses e e' are adapted to receive the extremities of the segment A of the hoop or finger band. One end of said segment is firmly secured in its seat, in its recess e' in 35 one of the wings b', by a screw or rivet passed transversely through the lug and the band, as seen in dotted lines in Fig. 1, or in any other suitable way; or the segment A may be integrally whole at one end with one of said wings 40 b', and be an extension thereof. The free opposite end of the segment A is bifurcated or forked, as seen plainly at a in Fig. 6. An orifice, b², is formed transversely through the wing b of the head, as seen in Figs. 1 and 3.

45 This orifice is of somewhat greater diameter in the direction across the wing or lug, as seen plainly in Fig. 4.

C is a sectional sleeve, adapted to be seated in the orifice b², and of an exterior diameter 50 substantially equal to the short diameter of said orifice. One of the halves of this sleeve

is seen in Fig. 5, and it is shown seated in the orifice b² in Figs. 3 and 4. The side or wall of each half of the sleeve is cut away or recessed on the exterior, as shown at c, to receive and fit upon the opposite inner edges of the sides d d' of the forked end of the segment A, as plainly seen in Figs. 3 and 4. The interior of the sleeve is threaded to receive the short screw D, and this screw has the conically-shaped head d², and the sleeve has at its outer end a conical countersink, c', to receive and fit the screw-head.

The described devices operate as follows: The sleeve C being seated in the orifice b² in 55 the wing b, and the forked end of the band being slipped into place in the recess e in said wing, the sleeve is, by the engagement of the edges of the fork of the segment A in its side recesses, c, prevented from escaping from 60 said orifice, although said sleeve is free to move in the orifice, and the forked end of A is also free to be moved longitudinally in the recess e. When the screw D is introduced into 65 said sleeve and turned down tight in its place, its head d² operates to spread the split sleeve in the orifice b² in the direction across the wing from edge to edge and the sleeve bearing against the inner edges of the sides d d' of the forked end of segment A. This sidewise pressure binds the said forked end tightly in contact with the head or crown B and holds it in 70 the desired position in which it is adjusted. When it is desired to lengthen or shorten the segment A, the screw D is turned back slightly 75 in its seat, thus relieving the sidewise pressure, and the segment A may be drawn more out of or carried farther into the recess e, and the screw being turned down again the parts are secured together. By means of these de- 80 scribed devices the segment A may be readily and quickly adjusted to fit a finger, as desired, without the necessity of cutting or stretching 85 the band or in any way mutilating the ring.

It is obvious that both ends of the segment 90 A may be forked, and that the devices described for making one end adjustable in the head may be applied to both ends, and the segment be thus capable of longitudinal adjustment at either or both ends.

100 What I claim as my invention, and desire to secure by Letters Patent, is—

In a finger-ring, the combination of the head B, having the described recessed wing b, provided with orifice b², the segment A of the finger-band forked at one end, the sectional sleeve 5 C, having exterior recesses, c, and an interior female screw-thread with conical countersink c', and the screw D, having a conical-shaped

head, d², all constructed and arranged to operate as and for the purpose described.

HEINRICH HENRICH.
